CHRISTMAS TREE ORNAMENT

Dario Moranduzzo, Via Aretina 161, Florence, Italy

Filed Oct. 22, 1965, Ser. No. 87,817

Term of patent 14 years

(Cl. D29—1)

FIG. 1 is a front view of a Christmas tree ornament showing my new design, the opposite sides being substantially the same in appearance; and

FIG. 2 is a top plan view thereof, the bottom being substantially identical thereto except for the retention knot.

I claim:

The ornamental design for a Christmas tree ornament, as shown and described.
